UNITED STATES PATENT OFFICE.

MARCUS B. BEHRMAN, OF BROOKLYN, NEW YORK, ASSIGNOR TO THE LOX SEAL CORPORATION, OF NORTH BERGEN, NEW JERSEY, A CORPORATION OF NEW YORK.

SAFETY RAZOR.

Application filed June 1, 1921. Serial No. 474,095.

To all whom it may concern:

Be it known that I, MARCUS B. BEHRMAN, a citizen of the United States, and a resident of borough of Brooklyn, city of New York, 5 in the county of Queens and State of New York, have invented certain new and useful Improvements in Safety Razors, of which the following is a specification.

The invention relates to safety razors, and 10 particularly to combination razor and stropping devices. The principal object of the invention is the provision of an improved simple and effective device of this character, which is particularly adapted for use with 15 thin flexible blades, such as the well known blades having cutting edges at both sides, in which the blade is adjusted into shaving position by flexing or clamping its edge or edges over and against a guard or guards. 20 This is accomplished by mounting the blade on a movable member, so positioned in relation to the frame as to permit the insertion of a strop between the two, the blade moving from one stropping position to another 25 when the direction of stropping is reversed; and providing a member which is readily adjusted into position to hold the movable member stationary and flex or clamp the edge or edges of the blade in shaving position, when the device is to be used for shaving.

Other objects of the invention comprise the provision of improved forms of construction and combinations of parts, all as will 35 be more fully explained hereinafter in the following specification and particularly pointed out in the appended claims.

In order that a clearer understanding of the invention may be had, attention is here- 40 by directed to the accompanying drawings forming part of this application and illustrating certain embodiments of the invention. In the drawings,

Fig. 1 represents an enlarged transverse 45 vertical section through a construction embodying my invention;

Fig. 2 is a vertical section taken on line 2-2 of Fig. 1;

Fig. 3 is an end elevation of the construc- 50 tion shown in Fig. 1, the handle being broken away;

Fig. 4 is a top plan view of the same;

Figs. 5 and 6 represent vertical sections taken on line 5-5 of Fig. 4 with the top

blade clamping member removed and a strop 55 inserted through the device; Fig. 5 representing stropping of the blade in one direction and Fig. 6 in the opposite direction;

Fig. 7 is an enlarged side elevation of the parts of the device separated from each 60 other, the blade retaining means being shown in open position;

Fig. 8 is a top plan view of portions of the device located beneath lines 8-8 in Fig. 7; 65

Fig. 9 is an end elevation of a modified form of device; and

Fig. 10 is a side elevation of the form of device shown in Fig. 9.

Referring to the drawings, the frame of 70 the device comprises a member 1 which may be formed of sheet metal pressed into the form of an inverted arch, in transverse section, with its side edges bent outwardly and downwardly, portions of these side edges being 75 cut away to form guards or combs 2, 2. A handle member 3 is secured in any desired manner to the bottom of frame member 1 at the center thereof to extend downwardly therefrom, frame member 1 and handle 80 member 3 having a vertical opening 4 extending therethrough.

The razor blade 5 is supported on a movable member whereby the blade may be moved from one position to another in 85 stropping the same, to present different edge surfaces to the strop. In the construction shown in Figs. 1 to 8 of the drawings frame 1 is provided at its ends with upwardly turned ears 6, 6, having aligned openings 90 therethrough. These openings preferably take the form of vertical slots 6¹. The blade supporting member 7 is provided at its ends with downwardly extending lugs 8 having cylindrical pins 9 extending outwardly 95 therefrom, these pins being rotatively supported in the openings or slots 6¹ in ears 6 of the frame. Blade supporting member 7 has a central vertical opening 10 therethrough which is aligned with the opening 4 100 through the handle member 3 when member 7 is in its vertical position. Member 7 also, in the form of construction shown in the drawings, is provided with vertical openings 11, 11, therethrough, one at each side 105 of the central opening 10. Member 7 is provided with short annular upward extensions 12, 12, surrounding openings 11, integral

with, or secured to, member 7. In the form of construction shown in Fig. 2 member 7 may conveniently be made by a die casting process with extensions 12 and all other projecting parts integral therewith.

When blade 5 is a thin flexible blade of the well known form having cutting edges on opposite sides and three aligned openings through the blade, it may be positioned on member 7 by placing the blade on the member in such manner that upward extensions 12 of member 7 will enter the two end openings of the blade.

Blade 5 is secured on member 7 by a suitable securing device which is readily mounted in position and removed therefrom. This preferably takes the form of a bar 13 which is hingedly connected at one end by pin 14 to a lug 15 extending upwardly from the end of member 7. Bar 13 is provided with openings 16, 17, 17, which are adapted to align with openings 10, 11, 11, when bar 13 rests in its horizontal, or closed position, in which the upward extensions 12 of member 7 preferably extend into openings 17, 17, of bar 13.

Bar 13 may be latched in its operative position by any suitable means, such as a latch bar 18 hingedly connected to the end of bar 13 opposite from that at which pivot pin 14 is mounted. Supporting member 7 is provided with an outwardly extending lug 19 at its end opposite to that at which lug 15 is located, and latch bar 18 has an opening 20 therethrough into which lug 19 will extend when the latch bar is swung downwardly into the position shown in Figs. 3 and 10, lug 19 wedging within the opening, between the upper and the lower edges 40 thereof.

When a blade is thus mounted on the blade support the latter may be oscillated through a short arc from one side to the other of the vertical position of member 7. Member 7 and bar 13 are each of less width than the blade 5 secured therebetween, so that when member 7 is in its vertical or intermediate position the two edge portions of the blade will extend laterally beyond members 7 and 13 above the two guards or combs 2, 2. In this position the edges of the blade will be separated vertically from the guards 2, 2, by a distance sufficient to enable the insertion of a strop between the same. Insertion of the strop is facilitated when vertical slots 6¹ are used.

Member 7 is preferably given a somewhat V-shape, as shown, or is otherwise provided with a surface which will be engaged frictionally by a strop when the latter is passed through the device, the strop causing pivot pins 9 to rise to the top of slots 6¹. In Fig. 5 a strop 21 has been passed through the device, above the guards 2 and beneath member 7, member 7 extending downwardly

below guards 2 a sufficient distance to bend the strop as it passes through the device, to insure good frictional contact between the lower surface of member 7 and the upper surface of the strop. When the razor 70 is grasped by handle 3 and moved in one direction along the strop, as indicated by the arrow in Fig. 5, member 7 will be rocked by engagement with the strop, pivot pins 9 turning in the upper part of slots 6¹, and the rear edge of blade 5 pressed against the strop above one of the guards 2. When the razor is then moved in the opposite direction, as is shown in Fig. 6, member 7 will immediately be swung in the 80 opposite direction by engagement with the strop, so as to strop the opposite edge of the blade.

When the device is to be used as a razor a top clamping member 22 is mounted in 85 position. In the form of construction illustrated this comprises a rigid plate arched in its transverse direction, having lugs 23, 23, adapted to enter openings 17 in bar 13, and to pass downwardly through the upward annular extensions 12 of member 7 which are positioned within openings 17, and the openings in the razor blade through which extensions 12 pass. Member 22 is also provided with a downwardly extending centrally located pin 24 which is adapted to pass through opening 16 in member 13, the aligned opening 10 in member 7 and the central opening of the blade, and to enter the opening 4 in frame 1 and 100 handle member 3.

The passage of the pin 24 through these aligned openings will immediately have the effect of securing member 7 in its vertical position. Member 22 is then adjusted into 105 position to press the edge portions of the blade against guards 2 in shaving position.

In the form of construction illustrated a cylindrical member 25 extends upwardly into an interior space 26 provided in the 110 lower portion of the handle. Member 25 is provided with a socket 27 extending downwardly from its upper surface, this socket being provided with an internal screw thread. Pin 24 is provided with an 115 internal screw thread 28 formed about its lower portion. When the blade is to be clamped into shaving position the threaded end portion of pin 24 is inserted within the socket 27 and member 22 drawn down 120 by rotating member 25 about the pin 24, member 25 preferably being provided with a knurled knob 29 at its lower end.

Member 22 is arched to extend over member 13 so that its edge portions 30 will press against the upper edge portions of blade 5. Accordingly when the member 22 is screwed down it will flex the blade and press its edge portions down against the upper surfaces of guards 2 into shaving position. 130

The closeness of shaving desired may, of course, be adjusted by tightening member 22 more or less, as is well known.

In the preferred form of construction member 25 is permanently mounted within the shell portion 31 of handle member 3. This may be arranged by providing member 25 with a peripheral bead 32 a short distance above knob 29 and bending the lower edge 10 33 of shell 31 inwardly beneath bead 32, as is shown in Fig. 1.

The form of construction illustrated in Figs. 9 and 10 is similar to that previously described, but differs therefrom in that 15 frame member 1 is provided at its ends with downwardly extending lugs 6¹ having openings therethrough, member 7 having downwardly extending arms or flanges 8¹ at its ends, pins 34 extending through aligned 20 openings in the lower portions of arms 8¹ and through lugs 6¹, to form the pivots for member 7.

It will be noted that the provision of 25 vertical slots 6¹ in ears 6, in the construction shown in Figs. 1 to 8 of the drawings, enables pivot pins 9 to rise from the bottom of the slots when a strop is inserted, so as to give more clearance for the strop. This 30 enables strops of different thickness to be used, and also makes the device work better as a stroppler. member 7 and the blade tilting very easily, and the blade edge having a wider swing towards and away from the strop. When the device is used as a razor 35 pins 9 will rest firmly on the bottom of slots 6¹, in which position the edges of the blade may be as close as is desired to the guards, so that knob 29 need only be turned a few turns to flex the blade edges down against 40 the guards.

I consider that my invention is one of broad scope, not limited to the particular forms of construction which have been particularly described, by way of illustration 45 but not of limitation. Stropping devices per se somewhat similar to those described herein are known, and means for clamping a blade in a razor, similar to those described herein, are known; but I believe it to be 50 broadly new to position a blade holder above the guards so that the blade may be stropped in situ, and to provide means for flexing the blade edges into shaving position against the guards. Other features of the invention 55 are also thought to be of considerable scope, as is indicated by the following claims.

What I claim is:

1. In a safety razor, the combination of 60 a frame with guards at opposite sides thereof, a blade holder movably connected to said frame, in such manner that pressure applied thereto will tilt the same towards one side or the other, and so as to permit the passage of a strop between the same and said guards, and means for simultaneously pressing the

edge portions of a flexible two-edged blade held by said holder against said guards, in shaving position.

2. In a safety razor, the combination of 70 a frame with guards at opposite sides thereof, a blade holder positioned to hold a blade with its edges unsupported above said guards, a space being provided between the guards and blade edges, and below said holder, for the passage of a strop, and means 75 for flexing the blade-edges down against said guards, in shaving position, and so holding them.

3. In a safety razor, the combination of 80 a frame with guards at opposite sides thereof, a blade holding member pivoted to said frame, so arranged that the edges of a two edged flexible blade will project from the same, above said guards, and positioned to permit the passage of a strop beneath the 85 same and the blade, and above said guards, and means adjustable into position for simultaneously pressing the edge portions of the blade against said guards, in shaving position. 90

4. In a safety razor, the combination of a frame having a guard at one edge, a blade-holder pivoted to said frame, so arranged that a flexible blade held thereby may be stropped by reciprocating said frame along 95 a strop extended between said blade holder and guard, and means for securing said blade holder in fixed position and flexing the edge portion of a blade held thereby against said guard, in shaving position. 100

5. In a safety razor, the combination of a frame having a guard and a handle, a holder for a perforated flexible blade, pivoted to said frame, so arranged that a blade held thereby may be stropped by reciprocating 105 said frame along a strop extended between said blade-holder and guard, said holder having perforations corresponding to those of the blade, and a clamping plate having positioning pins adapted to enter perforations in the blade and holder, said plate being adapted to clamp the blade edge in shaving position against the guard. 110

6. In a safety razor, the combination of a frame with guards at opposite sides thereof, a blade holding member pivoted to said frame, so arranged that the edges of a two edged flexible blade will project from the same, above said guards, and positioned to permit the passage of a strop beneath the 115 same and the blade, and above said guards, a clamping plate adapted to be positioned above the blade and to press the edge portions of the blade against said guards, and means for drawing said plate down to so 120 press the edge portions of the blade. 125

7. In a safety razor, the combination of a frame having a guard, a hollow handle, a perforated holder for a perforated flexible blade tiltably secured to said frame, so ar- 130

- ranged that a blade held thereby may be stropped by reciprocating said frame along a strop extended between said blade-holder and guard, a clamping plate having a pin 5 adapted to be extended through perforations in the blade and holder, into said handle, and means for drawing said pin down into said handle to clamp the blade edge against said guard.
10. 8. In a safety razor, the combination of a frame with guards at opposite sides thereof, a blade holder positioned to hold a blade with its edges unsupported above said guards, a space being provided between the 15 guards and blade edges, and below said holder, for the passage of a strop, said blade-holder and blade being perforated, a clamping plate adapted to be positioned above said blade, with a projection entering 20 aligned perforations in the blade and holder, and means for drawing the plate down to press the blade edges against the guards.
9. In a safety razor, the combination of a frame bent to provide upwardly extending 25 side edges, a blade support tiltably supported by said frame between said edges, with its upper, blade supporting surface above the level of said edges and with a surface adapted to frictionally engage and bend 30 a strop below the level of said edges, the construction being adapted to permit the passage of a strop over said edges and below said last named surface, and means for removably securing a blade on said upper surface with its opposite cutting edges extending 35 unsupported above said frame side edges.
10. In a safety razor, the combination of a frame bent to provide upwardly extending side edges, with guards formed thereon, a 40 blade supported tiltably supported by said frame between said edges, with its upper, blade supporting surface above the level of said edges and a surface adapted to frictionally engage a strop below the level of said 45 edges, and a bar for removably holding a blade on said upper surface with its opposite cutting edges extending beyond said support and bar, above said frame side edges, said bar, blade support and frame 50 having openings therethrough adapted to be aligned when said support is in its vertical or intermediate position.
11. In a safety razor, the combination of a frame bent to provide upwardly extending 55 side edges, a blade support tiltably supported by said frame between said edges, said blade support having pivot pins so supported by said frame as to permit a limited vertical movement to the same, said blade 60 support having a blade supporting surface above the level of said edges and having a surface adapted to frictionally engage and bend a strop passed over said edges and under said last named surface, the passage of the strop serving to lift said pivot pins 65 to their upper limit of movement, and means for removably securing the blade on said blade supporting surface with its opposite cutting edges extending unsupported above 70 said frame side edges.
12. In a safety razor, the combination of a frame, bent to provide upwardly extending side edges, and having vertical flanges at its ends, a blade support tiltably supported by said frame between said edges, said blade 75 support and flanges having coacting pins and vertical slots, and means for removably supporting a blade on the upper surface of said blade support with its opposite edges extending above said frame side edges, said 80 pin and slot connection permitting said blade support to rise when a strop is inserted over said side edges and under said blade support, and said blade support having a surface adapted to be frictionally engaged by the strop.
13. In a safety razor, the combination of a frame with guards at opposite sides thereof, a blade holder positioned to hold a blade with its edges extending above said guards, 85 said blade holder having a pin and slot connection with said frame, to provide upper and lower positions therefor, so that a space will be provided between the guards and blade edges, and below said holder, for the 90 passage of a strop, when said blade holder is in its upper position, and means for clamping the blade-edges down against said guards, in shaving position.
14. In a safety razor, the combination of 95 a frame with guards at opposite sides thereof, a blade holder tiltably supported by said frame to hold a blade with its edges extending above said guards, said blade holder having a pivot pin and slot connection with said 100 frame to provide upper and lower positions for the axis of oscillation thereof, so that a space will be provided between the guards and blade edges, and below said holder, for the 105 passage of a strop, when said blade is in its upper position, said blade holder having a lower surface adapted to be frictionally engaged by the strop, and means for clamping the blade-edges down against said guards in 110 its intermediate position.
- Signed at New York city, in the county of New York, and State of New York, this 26th day of May, A. D., 1921.

MARCUS B. BEHRMAN.
